DESIGN FOR A PICTURE FRAME OR SIMILAR ARTICLE

Gerald D'Angelo, New York, N. Y.

Application April 14, 1948, Serial No. 145,724

Term of patent 3½ years

(Cl. D29—20)

To all whom it may concern:

Be it known that I, Gerald D'Angelo, a citizen of the United States of America, and a resident of the county of Kings, city of New York, and State of New York, have invented a new, original, and ornamental Design for a Picture Frame or Similar Article, of which the following is a specification, reference being had to the accompanying drawing, forming a part thereof.

In the drawing:

Fig. 1 is a view in front elevation of a picture frame or similar article showing my new design; Fig. 2 is a side elevational view thereof; and

Fig. 3 is a top plan view thereof, with the detachable top frame member removed.

The dominant features of my design reside in the portion shown in full lines.

I claim:

The ornamental design for a picture frame or similar article, substantially as shown and described.

GERALD D'ANGELO.
